VALVE FOR CORE DRILLS

Alfred C. Catland, Alhambra, and John H. Howard, Huntington Park, Calif.; said Catland assignor to Globe Oil Tools Company, Los Nietos, Calif., a corporation of California

Original application January 14, 1936, Serial No. 59,076, now Patent No. 2,089,482, dated August 10, 1937. Divided and this application July 6, 1936, Serial No. 88,991

4 Claims. (Cl. 251—167)

This invention relates to a valve and relates more particularly to a valve for use on the core receiving barrel of a core drill. A general object of the invention is to provide a practical dependable and improved valve for a core barrel.

Another object of this invention is to provide a valve for a core barrel that embodies a replaceable valve seat dependably locked against loss or displacement.

10 Another object of this invention is to provide a valve for a core barrel embodying a threaded valve seat and simple, dependable means for positively locking the valve seat in place.

Another object of this invention is to provide 15 a valve of the character mentioned in which the means for locking the valve seat against displacement may also serve to prevent large objects from entering the valve seat and from interfering with the operation of the valve.

20 Another object of this invention is to provide a valve of the character mentioned that is very simple and inexpensive.

The various objects and features of our invention will be fully understood from the following 25 detailed description of a typical preferred form and application of the invention, throughout which description reference is made to the accompanying drawing, in which:

Fig. 1 is a side elevation of a typical core drill embodying the valve of the present invention 30 with a portion broken away to illustrate the valve in side elevation. Fig. 2 is an enlarged longitudinal detailed sectional view of the valve being a view taken as indicated by line 2—2 on Fig. 1. Fig. 3 is a transverse detailed sectional view 35 taken as indicated by line 3—3 on Fig. 2 and Fig. 4 is a side elevation of the valve seat removed from the body of the valve.

This application is a division of our co-pending 40 application entitled Core drill construction, Serial No. 59,076, filed January 14, 1936, which has matured into Patent No. 2,089,482, granted August 10, 1937.

The valve provided by the present invention is 45 adapted to be embodied in well core drills of various types and designs. In the following detailed description we will describe the valve as embodied in a more or less typical rotary core drill for use in the rotary method of well drilling. It is to be understood that the invention is not 50 to be construed as limited or restricted to the specific form or application about to be described, but that it is to be taken as including any features or modifications that may fall within the 55 scope of the claims.

The typical core drill illustrated in the drawing includes an outer barrel 10 carrying a suitable bit head 11^a. The cutting head 11^a is secured to the lower end of the barrel 10 by a suitable sub 17. The typical head 11^a has a plurality 5 of spaced cutting blades 18 for making an annular cut in the earth formation to leave an upstanding core. A sub or connecting member 15 is provided on the upper end of the barrel 10 and has a threaded pin 16 for facilitating the connection 10 of the drill with a tubular drilling string. An inner barrel 11 is arranged longitudinally within the outer barrel 10 to receive the core cut or formed by the head 18. A thickened portion or collar 20 is secured to the upper end of the inner 15 barrel 11 by welding or the like. The inner barrel 11 extends centrally through the outer barrel 10 with substantial clearance to leave an annular fluid passage 21 for the circulation fluid or 20 rotary mud pumped downwardly through the drilling string. The fluid passed downwardly through the annular passage 21 discharges from ports 19 in the bit head 11^a to cool the bit head, to provide proper turbulence in the well and to perform other functions. In accordance with the 25 rotary method of well drilling circulation fluid or rotary mud is pumped downwardly through the drilling string under comparatively high pressure and flows downwardly through the passage 21 in the outer barrel 10 to discharge at the bit 30 head 11^a.

The improved valve of the present invention includes, generally, a cage or body 22, means 14 removably securing the body 22 to the inner barrel 11, a removable valve seat 30 in the body 35 22, means 13 for locking the valve seat 30 against displacement, and a valve 34 for cooperating with the seat 30.

The valve body 22 is provided at the upper 40 end of the inner barrel 11 to carry the valve seat 13 and to provide a cage for the valve 34. The lower portion of the body 22 is cylindrical to fit within the collar 20 of the inner barrel 11. The upper portion of the body 22 projects 45 upwardly beyond the upper end of the collar 20. The body 22 has an annular downwardly facing shoulder 24 which may seat downwardly against the upper end of the collar 20. A central socket or opening 25 extends upwardly in the body 22 from its lower end and is in communication with the interior of the inner barrel 11. The upper end of the body 22 is preferably 50 hemispherical to effectively divert the downwardly flowing circulation fluid discharged into the outer barrel 10. A valve chamber 26 is formed 55

in the upper projecting portion of the body 22. Circumferentially spaced lateral ports 27 extend through the wall of the body 22 to have communication with the chamber 26. In accordance with the invention the valve body 22 is provided with a central opening 28 connecting the opening 25 with the chamber 26. The opening 28 is of less diameter than the opening 25 and the chamber 26.

10 The means 14 for removably securing the valve body 22 to the inner barrel 11 is fully described and claimed in our co-pending application referred to above. The means 14 includes a plurality of latches 35 carried by the body 22 to cooperate with the collar 20. The upper ends of the latches 35 are pivotally connected with the valve body 22 above the collar 20. Spaced webs 36 are provided on the valve body 22 between its ports 27 and the upper portions of the latches 35 project between the spaced webs 36. Pivot pins 38 are carried by the spaced webs 36 to pivotally support the latches 35. Each latch 35 is provided at its lower end with a lug 39. The lugs 39 are provided on the inner sides of the latches 35 and are substantially cylindrical in transverse cross section. Circumferentially spaced sockets 41 are provided in the valve body 22 and circumferentially spaced openings 40 are provided in the wall of the collar 20. The openings 40 and sockets 41 are related to register when the body 22 is in the proper rotative position. The lugs 39 are adapted to extend through the openings 40 into the sockets 41 to securely latch the valve body 22 to the collar 20 of the inner barrel 11. The latches 35 are proportioned so that their outer sides have only slight clearance with the interior of the outer barrel 10 whereby the outer barrel serves to prevent the displacement of the lugs 39 from the openings 40 and sockets 41. Thus the latches 35 cannot become freed or unlatched during operation of the drill and serve to dependably secure the valve body 22 to the inner barrel 11.

45 The valve seat 30 is provided in the valve body 22 to be engaged or sealed against by the valve 34 to prevent the downward flow of the circulation fluid into the inner barrel 11. In accordance with the invention the seat 30 may be a simple, tubular member. The seat 30 is preferably hardened to resist the eroding action of the fluid and to be long wearing. The valve seat 30 is removably arranged in the opening 28 of the body 22. In the preferred construction the seat 30 is threaded in the opening 28. The seat 30 is of sufficient length to project downwardly into the body opening 25 when its upper end is above or flush with the lower wall of the chamber 26. Thus the seat 30 completely lines the opening 28. An annular seating surface 37 is provided on the upper end of the seat 30 to receive the valve 34. The surface 37 is provided at the upper inner corner of the tubular seat 30 and is concaved.

55 The means 13 for locking the removable valve seat 30 against displacement is a feature of the invention. The means 13 operates to positively lock the tubular valve seat 30 against unthreading from the opening 28. In accordance with the invention the means 13 includes one or more notches 31 in the lower end portion of the seat 30. The notches 31 are open at the lower end of the seat 30 and occur in the portion of the seat which projects downwardly from the upper wall of the opening 25. The notches 31 are preferably flat walled or rectangular as illustrated

in the drawing. The means 13 further includes one or more lock bars 32. The bar or bars 32 is or are provided to cooperate with the notches 31. In the particular form of the invention illustrated in the drawing there are two diametrically opposite notches 31 and a single bar 32 is provided to cooperate with the two notches. It is to be understood that the invention contemplates the embodiment of independent lock bars 32 for cooperating with the individual notches 31. The bars 32 are rectangular or square in transverse cross section to have effective cooperation with the walls of the correspondingly shaped notches 31.

15 In accordance with the invention the bar 32 is secured to the valve body 22 so that its cooperation with the notches 31 locks the seat 30 against rotation and unthreading. The opposite end parts of the bar 32 may be welded to the adjacent walls of the opening 25 as illustrated at 33 in the drawing. The welding at 33 serves to rigidly connect the bar 32 to the body 22 so that the bar cooperating with the notches 31 securely locks the seat 30 against unthreading. Where a single bar cooperates with both notches 31 it extends 25 diametrically across the open lower end of the seat 30 and may serve as a strainer to prevent large objects from entering the seat 30 and from interfering with the operation of the valve 34. Thus the lock bar 32 may serve two functions, 30 namely, to lock the seat 30 against loss and to strain the fluid entering the seat, the former being the primary function of the bar.

35 The valve 34 is provided to cooperate with the surface 37 to prevent the downwardly flowing circulation fluid from entering the upper end of the inner barrel 11 to erode or wash away the core received by the inner barrel. In practice the valve 34 may be a simple ball valve or spherical member as illustrated in the drawing. The valve 40 40 is proportioned to properly cooperate with the surface 37 and is adapted to move upwardly in the chamber 26 under the action of fluid forced upwardly through the seat 30. The valve 34 is adapted to be inserted in the chamber 26 prior 45 to the arrangement of the seat 30 in the opening 28 and when the seat 30 is threaded in the opening 28 it serves to dependably retain the ball valve 34 in the chamber 26.

50 During the operation of the drill the cutting head 11a operates to make an annular cut in the earth formation to leave an upstanding core which enters the barrel 11 from its lower end. Circulation fluid is continuously pumped downwardly through the drilling string to pass through the passage 21 and discharge from the ports 19. The valve 34 cooperating with the surfaces 37 serves to prevent this downwardly flowing fluid from entering the upper end of the barrel 11 and, therefore, prevents the eroding or washing away 60 of the core. The core entering the lower end of the barrel 11 may trap fluid, cuttings, etc. in the inner barrel and as the drilling progresses the core displaces this fluid and material upwardly in the inner barrel lifting the valve 34 from its seat surface 37. Thus the valve 34 is adapted to open to allow the discharge of fluid, etc., trapped in the inner barrel.

65 The hardened valve seat 30 presents the finished surface 37 against which the valve 34 may 70 seat and seal. The bar 32 cooperating with the notches 31 operates to dependably lock the seat 30 against rotation and unthreading from the opening 28. Accordingly, the excessive vibrations to which core drills are usually subjected 75

cannot cause loss or displacement of the valve seat 30 or the ball valve 34. The means 13 for locking the seat 30 against displacement is very simple and may be inexpensively embodied in the 5 valve structure. When it is desired to replace the ball 34 or the seat 30 the welding at 33 may be readily broken away or burned away with a suitable torch to free the bar 32 whereupon the seat 30 may be unthreaded from the opening 28. It 10 will be observed that the notches 31 may receive a suitable turning tool for the purpose of threading and unthreading the seat 30.

Having described only a typical preferred form and application of our invention, we do not wish 15 to be limited or restricted to the specific details herein set forth, but wish to reserve to ourselves any variations or modifications that may appear to those skilled in the art or fall within the scope of the following claims:

20 Having described our invention, we claim:

1. A valve for a core drill having an inner barrel including a valve body having a fluid opening, means for removably attaching the body to the barrel, a valve seat threaded in the opening, a 25 valve for cooperating with the seat, there being a notch in one extremity of the seat, and a member attached to the body and cooperating with the notch to prevent unthreading of the seat, the member extending across the opening to form a 30 strainer therein.

2. A valve for use on the core receiving barrel of a well drill including, a body to be applied to

the barrel, the body having an opening, a tubular valve seat threaded in the opening, a valve in the body cooperating with one end of the seat, the seat having a notch in its other end, and a bar fixed to the body and extending transversely 5 through the opening and cooperating with the notch to secure the seat against unthreading.

3. A valve for use on the core receiving barrel of a well drill including, a body to be applied to the barrel, the body having an opening, a valve 10 seat threaded in the opening and having a seat face on one end and having its other end portion projecting from the end of the opening, the extremity of said projecting end portion having spaced notches, a valve for cooperating with the 15 seat face, and a bar fixed to the body and cooperating with said spaced notches to prevent unthreading of the seat.

4. A valve for use on the core receiving barrel of a well drill including, a body to be applied to 20 the barrel, the body having an opening, a valve seat threaded in the opening and having a seat face on one end and having its other end portion projecting from the end of the opening, a valve member cooperating with the said seat, said projecting end portion having diametrically opposite notches, and a bar fixed to the body and cooperating with the notches to prevent unthreading of the seat. 25

ALFRED C. CATLAND. 30
JOHN H. HOWARD.
